HYDRAULIC JACK

Wingham J. Liddell and Leander C. Morse,
Oakland, Calif.

Application January 4, 1937, Serial No. 118,945

5 Claims. (Cl. 60—52)

This invention relates particularly to hydraulic jacks, although the method of operation outlined may be readily applied to any type of fluid-operated device in which a fluid is transferred back and forth between two closed containers, and is particularly directed to a hydraulic jack which may be operated in any position, as upright, inverted, reclined or inclined.

The main object of this invention is to provide a hydraulic jack which is operable in any position, ranging from upright to inverted, to permit its use in connection with bulldozing, shifting, easing, lifting, and other operations, and in any desired direction relative to the vertical.

Another object of the invention is to provide a jack with means presenting the fluid in storage continuously to the intake of a transfer pump, irrespective of the relative position of the jack and pump.

A further object of the invention is to provide a valve system which will operate in proper sequence irrespective of the relative position of the jack.

A still further object of the invention is to provide a follower in the transfer fluid container which will continuously maintain the fluid-displacement space in the container exactly equal to the instant volume of fluid contained therein, irrespective of transfer of fluid to or from the container.

Other objects and advantages of the invention will become apparent as the following description is read on the drawing forming a part of this specification, and in which similar reference characters are used to designate similar parts throughout the several views, of which;

Fig. 1 is a sectional elevation through the invention.

Fig. 2 is a fragmentary view, shown partly in section, and showing the lower portion of the jack in reclined position, showing the fluid urged to the intake of the pump.

Fig. 3 is a modification of the invention shown on a reduced scale.

Fig. 4 is an enlarged fragmentary sectional view showing a modification of the follower in a self-acting type requiring no external urging.

The usual hydraulic jack consists of a cylinder and a lift operating therein, a transfer-oil storage, a pump for transferring oil between the cylinder and storage, and a valve-controlled bypass for releasing the lift.

These features are all included in this invention, the working cylinder being shown at 10,

the lift or piston at 11, oil storage cylinder or container at 12, the pump at 13, and valve-controlled bypass at 14.

This invention resides in the method and means for maintaining the oil supply 15 in constant communication with the intake of the pump 13, irrespective of the relative position in which the jack is to be operated, such as the upright position shown in Fig. 1, or reclined position shown in Fig. 2.

The piston 11 has a load engaging head 16, and is provided at its lower end 17 with a leather cup packing 18 which is expanded to cooperate with the cylinder wall by means of a resilient expander 19, the packing 18 and expander 19 being secured to the lower end of the piston or lift 11 by known means such as a washer 20 and bolt 21. A stop groove 22 is formed annularly in the piston in spaced relation to its lower end, the purpose of which will be later described.

This piston or lift 11 is slidable in the cylinder 10, and the cylinder 10 has its upper and lower ends respectively secured in the container head 23 by threads 24, and in the jack base 25 by threads 26.

The transfer-fluid or storage cylinder 12 is mounted concentrically about the working cylinder 10 and has its lower end secured to the jack base by threads 27, and its upper end retained by the shoulder 28 formed on the head 23.

The exterior periphery 29 of the working cylinder 10, and inner periphery of the transfer-fluid cylinder 12 are finished to slidably receive the follower which includes the ring or annular piston 31 which encompasses the working cylinder, and an annular cup leather packing 32 which cooperates with the respective walls 29 and 30 and also encompasses the working cylinder.

A contracting resilient split ring 33 maintains the leg 34 of the cup leather 32 in contact with the wall 29 throughout its peripheral extent, and an expanding resilient split ring 35 maintains the cup leather leg 36 in contact with the wall 30 throughout its peripheral extent, the combination of piston, packing, and contracting and expanding rings forming a sealed follower requiring extraneous urging for positive continuous cooperation with the transfer fluid.

A compression spring 37 cooperates between the head 23 and the top of the piston 31, and is sufficiently compressible to permit transfer of all fluid from the working cylinder 10 to the displacement space defined by the space 38 between the cylinders and between the top 39 of the base and the cup leather packing 32, and

is sufficiently expansible, and exerts sufficient urge to lift or deliver all of the oil 15 except that contained in the passages and packing recess, to the intake 40 of the pump 13, in any 5 position of the jack, either inverted, inclined, reclined or upright.

This follower may be constructed in such manner whereby no extraneous urge is required, such as is illustrated in Fig. 4, in which the cup 10 packing 32 and resilient contracting and expanding rings 33 and 35 are duplicated on the upper side of the piston, in which the oil-contacting or lower packing prevents escape of fluid, and the air-contacting or upper packing prevents 15 ingress of air.

With this self-acting follower, the follower can only follow or move with variations in the volume of oil in the container, since the air-contacting packing prevents admission of air. Thus 20 the follower varies the displacement space in the container in exact proportion to the variation in volume of oil in the container.

The preferred embodiment however is shown in Fig. 1, in which the spring 37 maintains a constant pressure on the oil, making the cup packing 25 more effective.

To obviate any possibility of the lift or piston 11 being urged outwardly or dropping down out of the working cylinder 10 in inclined, reclined, 30 or inverted position, a latch 41 is mounted in the head 23 and cooperates with the annular grooves 22 and 42 respectively in the projected and retracted positions of the lift.

This latch is urged to cooperate with the respective grooves through the medium of a spring 43 and is retractable or releasable by means of the button 44 which is integral with the latch.

Thus, the piston may be forced down into the cylinder until the latch 41 catches in the groove 42, and when ready for operation, the button 44 40 is pulled outwardly, releasing the lift, after which the pump 13 may be brought into operation.

Similarly, when the lift reaches a predetermined projected position, the latch will cooperate with 45 the groove 22 and prevent further movement. The piston may be removed from the cylinder by merely releasing the latch and withdrawing the lift.

The pump 13 has a piston 45 slidably within 50 the cylinder 46, the piston rod 47 slidably operating through the gland 48 which is secured in or to the top of the cylinder. A lever 49 has one end pivoted in the bracket 50 and is intermediately pivoted to the piston rod 47 as shown 55 at 51, the handle extension of the lever being shown in end view at 52.

The intake connection 40 to the pump is controlled by means of a valve 53 urged by a spring 54 which is retained by a plug 55 which has a 60 passage 56 communicating with the pump cylinder. The intake 40 communicates with the chamber 38 through passages 57 and 58.

The pump discharge passage 59 communicates with the space between the valve 53 and plug 65, and through passages 60 and 61 with the working cylinder 10 through a passage 62, which 65 passage is controlled by a valve 63 which is urged to seat by means of a spring 64, the spring 64 being retained by a plug 65 having a passage 66 70 formed therethrough.

A bypass 14 linking passages 58 and 66 is controlled by a manually actuated valve 67 through the medium of a lever 68. Opening of this valve permits the piston 41 to be manually forced down 75 into the cylinder or manually projected or re-

moved, and also forms manually-controlled lowering means for the jack.

One side 69 of the base 25 is formed parallel to one side of the cylinder, so that the jack may be laid on its side for lateral or inclined operation.

Fig. 3 is a modification of the invention, in which the working cylinder 10 and storage cylinder 70 are mounted side by side, and they can also be mounted at right angles to each other, or in any other relative position, and still provide the same results. In this case, a cylindrical piston 71 is used with a cup leather packing 72, expander 73, washer 74 and screw 75, both cylinders being mounted on the same base 76, which is otherwise formed similarly to the base 25, and includes the pump 13, which for preservation of space would obviously be mounted somewhat as indicated, back of, or in front of the pair of cylinders, the spring 77 being retained and seated against the head 78. In either type, the follower reduces the effective volume of the transfer storage in exact proportion to the fluid transferred therefrom, and increases the effective volume in exact proportion to the fluid transferred thereto.

With operation of the jack in upright position, there is no appreciable difference over operation of other types of hydraulic jacks. However, in inclined, reclined, or inverted positions, the piston 31, through urge of spring 37, or with the structure shown in Fig. 4, without the urge of a spring, continuously delivers oil to the intake 40 as is clearly illustrated in Fig. 2, the piston 31 functioning as a follower and varying the effective displacement volume of the transfer storage exactly in accordance with variations in the volume of stored fluid.

It will be understood that variations in construction and arrangement of parts, which variations are consistent with the appended claims, may be resorted to without detracting from the spirit or scope of the invention, or sacrificing any of the advantages thereof.

I claim:

1. In a hydraulic jack having a cylindrical lift having an annular groove formed adjacent the upper end thereof, a working cylinder, an encompassing transfer-fluid container, a supply of transfer fluid, and a pump having an intake; a spring-urged piston operating within said transfer-fluid container maintaining said supply of fluid continuously available to the intake of said pump irrespective of the position of said jack relative to its normal upright position, and latch means releasable at will and engageable with said groove for fixedly securing said lift when in fully retracted position against projectional movement under the influence of fluid urged by said spring-urged piston or by said pump or under the influence of gravity when said jack is inclined, reclined or inverted.

2. A hydraulic jack comprising a base, a working cylinder and a lift operating therein, a concentric transfer cylinder having a pump-intake passage in communication with the lower end thereof, a fluid pump, a ring piston operating between said cylinders, and a spring urging said piston toward said lower end, delivering fluid through said passage when said jack is in an inclined, reclined, or inverted position; a groove formed adjacent each end of said lift, and a latch and manual releasing means therefore mounted adjacent the top of said working cylinder, said latch fixedly securing and locking said lift against removal from said working cylinder and fixedly securing and locking said lift against

projection from its most retracted position in the working cylinder under the influence of gravity or urging of said spring acting through said fluid or under the influence of pressure transmitted through said fluid by said pump.

5 3. A hydraulic jack comprising a base, an operating cylinder secured to said base, a supply cylinder encompassing said operating cylinder and secured to said base, a head common to both cylinders and secured to the top of said operating cylinder, a ring piston operating between the walls of said operating cylinder and supply cylinder, a cup leather ring packing for the lower end of said ring piston and resilient expanding and contracting means respectively for the respective outer and inner peripheral walls of said ring packing, a spring urging said ring piston toward the bottom of said supply cylinder, and a lift piston operating in said operating cylinder and having a cup leather packing affixed to the lower end thereof and resilient expanding means for the annular wall of said cup leather, said lift piston being normally urged for projection by said spring acting through said fluid, a pump for transferring fluid from said supply cylinder to said operating cylinder, and a bypass between said operating cylinder and said supply cylinder and a manually controlled valve controlling said bypass and, 20 latch means associated with said head and cooperatively related to said lift piston, fixedly securing and locking said lift piston against projection from its most retracted position, under the urging of fluid urged either by said spring or by said pump, and also against gravitational influences, and, manual releasing means for releasing said latching means at will.

25 4. A structure as claimed in claim 3, in which said latch means comprises an annular groove formed adjacent each end of said lift piston, and a plunger associated with said head and spring urging means therefor, said manual releasing means being associated with said plunger, said latching means being cooperatively related to said grooves for retaining and locking said operating piston against projection when said jack

is inclined, reclined or inverted, against the influence of gravity or pressure applied through said fluid, and for stopping said operating piston against complete removal from said operating cylinder said piston being freed for complete removal or for projection upon manual release of said latching means.

5 5. A hydraulic jack comprising a base, an operating cylinder threadedly secured on said base, a supply cylinder encompassing said operating cylinder and forming an annular chamber therebetween, a ring piston operating in the annular chamber, a head threadedly secured to the top of said operating cylinder and having a shoulder securing the upper end of said supply cylinder and coaxially aligning said cylinders and permitting said head to be screwed onto said operating cylinder, a compression spring cooperating between said head and said ring piston for continuous urging thereof, a lift piston slidable in said operating cylinder, a pump mounted on said base, a valve-controlled intake passage communicating between said pump and said annular chamber, a valve-controlled discharge passage communicating between said operating cylinder and said pump and a bypass communicating between said operating cylinder and said annular chamber, a manually controlled valve for said bypass for controlling passage of fluid from said operating cylinder to said annular chamber at will, a square shouldered annular groove formed adjacent each end of said lift piston, a latch having a square face and reciprocally mounted in said head for cooperation with said grooves respectively for locking said lift piston when in completely retracted position against projection and in projected position against complete removal from said operating cylinder, a spring urging said latch to cooperate with said grooves, and manually controlled means associated with said latch for releasing said latch at will to free said lift piston for projection or complete removal.
